MARKING AND COMBINED MARKING AND SPREADING MACHINE

Erik Friis Hansen, New York, N. Y.

Application January 16, 1940, Serial No. 314,056

17 Claims.

(Cl. 101—121)

This invention pertains to new and useful improvements in marking, and combined marking and spreading machines.

In course of the manufacturing of clothing, it is generally the custom to make a considerable quantity of a certain size or style. For this purpose, it is usual to spread layer after layer of the cloth to be used on top of each other until the desired quantity has been laid out; paper patterns are then placed on top of the upper layer of cloth, and the contours are marked with chalk by the operator; however, this process naturally requires considerable time.

In the present method forming the subject matter of this invention, the marking is performed while the machine is traveling over the surface of the cloth, and, consequently, this process naturally will require only a fraction of the time previously needed.

In placing the patterns individually on top of the cloth, as is now the common practice, it depends on the skill and careful handling of the operator to avoid as much as possible any waste; however, according to the method of the present device, as hereinafter described, the patterns are laid out by competent operators and gathered into perforated units, which at the time of use are mounted on a roller, thereby all waste practically becomes eliminated.

Furthermore, the same patterns will thus lend themselves to repeated use, assuring a consequent elimination of waste at all times.

With the above and other objects in view, this invention consists of the novel features of combination, construction and arrangement of parts, hereinafter fully described, claimed, and illustrated in the accompanying drawings, forming part of this application, and in which similar characters of reference indicate corresponding parts in all views, and in which:

Figure 1 is a longitudinal sectional view of my device.

Figure 2 illustrates a perspective view of a vacuum member, or marking device.

Figure 3 is an elevational view, partly in section, of a powder roller.

Figure 4 is a similar view as Figure 3, showing a modification of the latter.

Figure 5 is a section taken on the line 5—5 of Figure 4.

Figure 6 is a view similar to Figure 5, showing a modification of the latter.

Figure 7 is a cross sectional view, showing a further modification of Figure 5.

Figure 8 is a plan view, showing a roller with a pattern unit attached thereto.

Figure 9 is a section taken on the line 9—9 in Figure 8.

Figure 10 is a cross section taken on the line 10—10 of Figure 9.

Figure 11 is a cross section taken on the line 11—11 of Figure 9.

Figure 12 is a longitudinal view, showing a modification of my device proper.

Figure 13 is a fragmentary perspective view, showing a double form of a hollow blade, to be used in a spreading machine, as shown in Figure 12.

Figures 14 and 15 are diagrammatical views, showing the spreading knife, or blade in different positions.

Figure 16 shows a longitudinal sectional view of a conventional form of a spreading machine 20 with my marking device applied thereto.

Referring more particularly to the drawings, and especially to Figure 1, 20 indicates a table having legs 21; said table is provided with rails 22, which serve as tracks for rollers 23, the latter being mounted on the side members 24 of the machine proper.

Upon said table is arranged or spread a number of layers of cloth, which latter is secured to the table 20 by clamping members 25, which may have an operating string attached thereto, and which members are pivoted to the brackets, as shown at 26; said brackets being adjustably arranged upon the table 20.

When the layers of cloth have been spread upon the table a marking member 27, shown in Figure 2, is arranged underneath the top layer of said cloth.

The said marking member comprises a hollow central body 27 formed with perforations 28 therein, said central body is provided with a ribbed upper surface 29 to eliminate friction, while blade-like extensions 30 are formed upon each side thereof. Said marking member 27 has a tube 31 attached to its central hollow portion 27, by means of a hollow shaft 33, which terminates said hollow portion 27, and which shaft, in turn, is supported in slides blocks 34; the tube 31 is connected to a motor 32 adapted to supply vacuum to the hollow portion 27.

A powder roller 35 is arranged in the same block member 34 above the hollow portion 27, while in between said roller 35 and the marking member 27 is arranged the top layer 36 of the cloth and also on top of the latter a perforated paper pattern 37 which at one end is secured by

the clamping members 25; the other end of said paper pattern is wound around a roller 38 supported in openings 39 of the frame members 24.

Rollers 40, which may be subjected to a pressure by means of springs or cogs, are movable in slots 41 in the frame 24, and insure proper contact of the paper pattern with the top layer of the cloth.

When the machine in operation is traveling over the cloth and the vacuum is applied to the hollow portion 27, powder from the powder box or roller 35 is sucked by means of the vacuum in said hollow portion 27 through the perforations 42 of the paper pattern 37, leaving a distinct marking upon the surface of the top layer 36 of the cloth.

The slideable blocks 34 are adjustably connected by a chain 43 to sprockets 44 in order to regulate the heights of the marking member 72 and roller 35 in relation to the number of layers of the cloth. The said adjustment is accomplished by means of a ratchet 45 and pawl 46.

As shown in Figure 3, the powder box or roller 35 comprises a cylindrical member 47 made, for instance, of meshed wires, the surface of which is covered by a thin cheese cloth-like material. At each end said rollers are provided with studs 49 adapted to be journaled in the slideable block members 34.

As shown in Figure 4, the said rollers may also consist of a rubber material 50, provided with fine slits 51 therein.

The modification shown in Figures 4 and 5 will clearly lend themselves to be used with a liquid marking material disposed therein.

Figure 5 shows that the contents of the tube illustrated in Figure 3 may well consist of a sponge or felt-like material, saturated with a marking liquid.

In Figure 7 is shown a powder box 53 of a substantially rectangular shape, said powder box is at its bottom provided with a perforated surface 54 in the form of a cheese cloth. A three-way valve 55 is secured to the top of the powder box 53 so that the latter may be connected to a vacuum source as well as to a compressed air supply.

In using the powder box, or member 53, the vacuum supply of the hollow member 27 is shut off, as in this case compressed air forces the powder in the box 53 through the perforation 42 of the paper pattern 37 on top of the layer 36 of the cloth on to the latter. The powder box proper has an outer surface consisting of, for instance, a wire-mesh, which, in turn, is covered within by a cheese-cloth like material.

Upon a return movement of the machine over the cloth any excess amount of powder may be removed by in turn applying the vacuum to the box member 53.

By means of the bolts 56, the marking machine may be attached to any conventional shape of spreading machine.

Thus the bolt 56 may attach the marking machine shown in Figure 1 to the spreading machine, as shown in Figure 16; and it would from this appear that the device shown in Figure 16 may serve as an ordinary spreading machine, and the machine shown in Figure 1 as a marking machine alone.

As shown in Figures 8, 9, 10 and 11, the perforated paper pattern 37 is secured to the roller 38 by means of a bar 57, fitting into a shaft 58, while rings 59, in turn, are slipped over the ends of the roller, thereby securing said bar in place.

The roller 38 may have disposed on its shaft a spring 60 serving to bring about a desired tension between said roller and the paper pattern 37.

The modification illustrated in Figure 12, shows a machine 24' made for spreading and marking.

In this construction a double set of hollow members 27' are employed; said members will in the respective positions shown in Figures 14 and 15 tend to tuck the cloth under the clamping members 25.

The hollow members 27' are secured at each end to members 61, which are pivoted at 62 to the slideable block 34'; said hollow members 27' may by means (not shown herein) be placed in position, as indicated in the Figures 14 and 15.

The spreading member 27' can spread two pieces of cloth at the same time, or one piece of cloth and the paper pattern, while doing the marking simultaneously.

The block members 34' are provided with extensions 63, whereby to accommodate the rollers 40' and the paper pattern roller 38'.

By this construction any adjustment by means of the chain 43' and sprocket 44' automatically raises and lowers all members secured to blocks 34' and the extensions 63.

If desired or deemed necessary a flexible drive 64 may be provided from the wheels 23' to the paper pattern roller 38'.

As shown in the modified form in Figure 12, the powder roller 35' is disposed between the hollow members 27'.

In regard to the construction shown in Figure 12, either one of the hollow members 27' will, depending upon the direction of the movement of the machine, as illustrated in details in Figures 14 and 15, perform the marking of the cloth, as previously described in Figure 1.

The frame 24' shows means in the form of recesses 65, whereby to accommodate rolls of cloth 66 during the spreading.

Figure 16 shows a conventional type of spreading machine for carrying roll of cloth 66'; said cloth is guided over rollers 67 and 68, and is guided further by rollers 69 over the members 27' as shown in Figures 14 and 15.

The conventional flat spreading blades used, are replaced in the machine shown in Figure 16 by the hollow members 27', while the powder box 35' is similarly arranged in the block member 34'.

The rollers 40' and the paper pattern roller 38' are carried by a special frame member 24'', which in turn is secured to the frame members of the conventional type of spreading machine in any suitable manner.

It is obvious that slight changes may be made in the form, construction and arrangement of the several parts, as shown, within the scope of the appended claims, without departing from the spirit of my invention; and I do not, therefore, wish to limit myself to the exact form of construction and arrangement shown and described herein.

What I claim as new and desire to secure by Letters Patent of the United States, is:

1. A machine for marking, and combined marking and spreading of cloth, comprising a frame member adapted to travel over a table, block members adjustably arranged in said frame member, a powder roller or box disposed in said block members, and a cloth-spreading member connected to said block members, said spreading member being formed with a vacuum therein, substantially as and for the purpose set forth.

2. A machine for marking, and combined mark-

ing and spreading of cloth, comprising a frame member adapted to travel over a layer of cloth arranged upon a table, block members adjustably arranged in said frame member, a powder roller or box disposed in said block members, and a cloth-spreading member cooperating with said powder roller, said cloth-spreading member having a vacuum chamber formed with perforations therein, hollow shafts in continuation of said vacuum chamber and adapted to connect said spreading member to the block members, and means associated with said vacuum chamber, whereby to create a vacuum in the latter, said spreading member being formed with a ribbed upper surface.

3. A machine for marking, and combined marking and spreading of cloth, comprising a frame member adapted to travel over a number of layers of cloth arranged upon a table, means for securing said cloth to the table, block members adjustably arranged in said frame member, a powder roller or box disposed in said block members, and a cloth-spreading member having blade-like projections upon each side thereof, and being adapted to cooperate with said powder roller, said cloth-spreading member having a vacuum chamber formed with perforations therein, hollow shafts in continuation of said vacuum chamber, adapted to connect said spreading member to the block members, and means associated with said vacuum chamber, whereby to create a vacuum in the latter, and ribs formed upon the upper surface of said spreading member.

4. A machine for marking, and combined marking and spreading of cloth, comprising a frame member adapted to travel over a number of layers of cloth arranged upon a table, means for securing said cloth to the table, block members adjustably arranged in said frame member, a substantially cylindrically shaped powder roller formed with a sieve-like surface and disposed in said block members, a cloth-spreading and marking member cooperating with said powder roller and being mounted in said block members, and a paper pattern arranged on top of a layer of cloth, said layer of cloth and paper pattern being disposed between said powder roller and cloth spreading member, the latter having blade-like projections upon each side thereof and a vacuum chamber formed with perforations therein, hollow shafts in continuation of said vacuum chamber adapted to connect said spreading and marking member to the block members, and means associated with said vacuum member, whereby to create a vacuum in the latter.

5. In a device, as claimed in claim 4, and wherein rollers movably mounted in the frame proper are adapted to insure a suitable contact of the paper pattern with the top layer of the cloth.

6. In a device, as claimed in claim 2, and wherein in the table is provided with rails, and rollers mounted upon the frame and adapted to travel upon said rails.

7. In a device, as claimed in claim 4, and wherein the block members are connected to the frame by a chain and sprockets, whereby to regulate the height of the spreading and marking member and the powder box member relative to

the layers of cloth, and means for arresting the block members in a desired position.

8. In a device, as claimed in claim 4, and wherein the powder box is formed with studs adapted to slidably engage the block members.

9. In a device, as claimed in claim 3, and wherein the powder box-roller is provided with a surface of material formed with tiny openings or slits therein.

10. In a device, as claimed in claim 3, and wherein a sponge-like material, provided in the powder roller, and saturated with a liquid may take the place of powder in said powder roller.

11. A machine for marking, and combined marking and spreading of cloth, comprising a frame member adapted to travel over a number of layers of cloth arranged upon a table, means for securing said cloth to the table, block members adjustably arranged in said frame member, a powder box disposed in the block members, and a cloth spreading member mounted in the latter and adapted for reciprocal movement, said cloth spreading member being adapted to cooperate with the powder box, and a three-way valve arranged at the top of said powder box, whereby a vacuum or compressed air may be applied, respectively, during operation, the upper layer of the cloth and a paper pattern on top of the latter, being arranged between said powder box and the cloth spreading member, substantially as and for the purpose set forth.

12. In a device, as claimed in claim 11, and wherein the perforated paper pattern is arranged upon a roller, a bar adapted to engage a shaft and secure said pattern to the roller, and rings mounted upon the ends of the roller, whereby to secure the bar in position.

13. In a device, as claimed in claim 11, and wherein said paper pattern is mounted upon a roller, a shaft supporting the latter, and a spring arranged upon said shaft, whereby to create a tension between the roller and paper pattern.

14. A machine for marking, and combined marking and spreading of cloth, comprising a frame member adapted to travel over a number of layers of cloth arranged upon a table, means for securing said cloth to the table, block members adjustably arranged in said frame member, a powder roller disposed in the block members, a double-set of cloth-spreading members associated with said block members, and means for connecting the latter to said spreading members, extensions arranged upon said block members, and pressure exerting rollers and a paper pattern roller mounted upon said extensions.

15. In a device, as claimed in claim 14, and having track-rollers mounted on the frame member of the spreading machine and wherein a flexible driving member is arranged between the paper pattern roller and said track-rollers.

16. In a device, as claimed in claim 14, and wherein the powder roller is disposed between the double set of cloth spreading members.

17. A device, as claimed in claim 1, and wherein in said marking and spreading machine is adapted to travel a straight course on a table.

ERIK FRILS HANSEN.
